(57) **CLAIM**

The ornamental design for a battery operated cutter, as shown and described.

DESCRIPTION

FIG. 1 is a front elevational view of a battery operated cutter showing my new design;

FIG. 2 is a top plan view thereof;

FIG. 3 is a rear elevational view thereof;

FIG. 4 is a bottom plan view thereof;

FIG. 5 is a left side elevational view thereof;

FIG. 6 is a right side elevational view thereof;

FIG. 7 is a front and top perspective view, showing the left side thereof;

FIG. 8 is a front and top perspective view, showing the right side thereof;

FIG. 9 is a front and bottom perspective view, showing the left side thereof; and,

FIG. 10 is a front and bottom perspective view, showing the right side thereof.

The broken lines depict portions of the battery operated cutter in which the design is embodied that are not considered part of the claimed design.
